UNITED STATES PATENT OFFICE.

JOHN SAMUEL DILLMAN AND WILLIAM B. KYLE, OF MOSCOW, IDAHO
TERRITORY.

FUMIGATOR.

SPECIFICATION forming part of Letters Patent No. 395,042, dated December 25, 1888.

Application filed May 4, 1888. Serial No. 272,811. (No model.)

To all whom it may concern:

Be it known that we, JOHN SAMUEL DILLMAN and WILLIAM BLACK KYLE, of Moscow, in the county of Nez Perces and Territory of Idaho, have invented a new and Improved 5 Gopher-Exterminator, of which the following is a full, clear, and exact description.

Our invention relates to a device for forcing poisonous fumes or gases into holes in the 10 earth to destroy gophers, rabbits, squirrels, or other burrowing animals; and the invention has for its object to provide a simple, inexpensive, and easily-operative device of this 15 character, which may be used effectively without allowing escape of the fumes toward or around the operator, which, if allowed, would sicken or injure him.

The invention consists in certain novel 20 features of construction of the exterminator, all as hereinafter described and claimed.

Reference is to be had to the accompanying 25 drawing, forming a part of this specification, and which is a longitudinal central sectional elevation of our improved gopher-exterminator, with earth and a burrow therein indicated in dotted lines, and the handle-rod of the plunger or piston partly broken away.

The exterminator consists of two main 30 sections or parts, an air and smoke pump, A, and a fire box or cylinder, B, which are arranged for easy connection with and disconnection 35 from each other by a screw or slip joint, a, so as to readily allow straw or wood, C, together with a suitable quantity of sulphur, to be placed in the fire-box, which at its outer or lower end is tapered to form a contracted nozzle, b, having a smoke-discharge opening, b'. The 40 tapering nozzle allows easy insertion of the fire-box into a hole, D, made in the earth by a gopher, rabbit, squirrel, or other burrowing animal.

The pump-section A of the device is made 45 with a barrel or cylinder, E, which is provided with an air and smoke tight piston, F, the rod f, of which plays through a stuffing-box, g, on the head G of the barrel, and is provided with a handle, f', by grasping which the piston may be reciprocated in the barrel. At its 50 lower part the barrel is provided with a partition-plate, H, having a hole, h, which is nor-

mally closed by a valve, I, which is supported by a lever, J, fulcrumed in the barrel in a manner to cause its weighted end j to carry the valve against the plate. At one side of it, and near the two extreme positions of the piston F, the barrel E is provided with openings e e', communicating with short lateral pipes K L, respectively, and in which are provided apertured partitions k l, forming seats, against which the inwardly-opening flap-valves M N, 60 hinged in the pipes K L, respectively, are adapted to close by an outward movement. At its upper part, and preferably about opposite the opening e, the barrel E has another side opening, e'', which communicates with the 65 interior of the hollow handle O of the device, which communicates at its lower end with the interior of the barrel E, below its valve-plate and valve H I, by means of another opening, e'', in the side of the barrel. In the upper 70 part, o, of the handle O, and near the barrel E, is fitted an apertured partition-plate, p, forming a seat against which a hinged flap-valve, P, fitted in the handle, may close, said valve opening outward, as shown in the drawing. 75

The operation of the exterminator is as follows: After the fire-box B is charged with the combustible material C and sulphur in proper quantity, as above described, and the material is lighted or fired, the air and smoke pump A 80 will be connected with the fire-box at the joint a, and when the fire-box is pushed into a burrowed hole, D, the pump-piston F will be worked by its rod and handle f f', which may be done with one hand of the operator, while 85 his other hand grasps the handle O on the pump-barrel to steady the device. On the upward or outward stroke of the piston the valves I M will close and the valves N P will open, and while the air which had previously 90 entered past the valve M is being forced by the rising piston past the valve P and through the hollow handle O to the interior of the barrel A, below the closed valve I, a fresh supply of air enters the barrel past the open 95 valve N, and the air forced through the handle O will also be forced downward through the combustible material C in the barrel to drive the sulphur-charged smoke into the 100 hole D. On the inward or down stroke of the

piston the valves N P will close, while the valves M I open, and the air, which had just previously entered the barrel A past the valve N, will be forced directly downward through the combustible material C, to carry the sulphur-charged smoke and fumes into the hole D. The piston is effective on both its inward and outward strokes or movements in forcing the deadly fumes into the burrowed hole to exterminate the animals therein, and as the valve I remains closed on the upstroke of the piston and closes promptly after its downstroke, and as the valve P also closes promptly on the downstroke of the piston, there will be no escape of these fumes from the device toward the operator, which, if allowed, would stupefy or injure him; hence the exterminator may be used with effectiveness by any person of ordinary intelligence with ease and entire safety.

The combustible material C may be employed with any substance or compound which will when fired generate deadly gases to be forced into the burrow, sulphur being a desirable substance commonly used for this purpose.

Having thus described our invention, what we claim as new, and desire to secure by Letters Patent, is—

1. An exterminator made with a pump and

communicating fire-box, said pump provided with air-inlets controlled by inwardly-opening valves located at or beyond the extremes of stroke of the piston, a downwardly-opening bottom valve, a hollow conduit or handle 35 opening to the pump-barrel below said bottom valve, and also above or beyond the piston, and an outwardly-opening valve fitted to the hollow conduit or handle, substantially as described, for the purposes set forth. 40

2. The combination, in an exterminator, of a pump, A, and fire-box B, adapted for detachable connection, said pump provided with a piston, F, a bottom air-outlet having a downwardly-opening valve, I, air-inlets at or beyond the extremes of stroke of the piston and controlled by inwardly-opening valves M 45 N, respectively, a hollow handle or conduit, O, connected with the pump-barrel above the piston F and below the valve I, and an outwardly-opening valve, P, fitted in the handle or conduit O, all constructed and arranged for operation substantially as described, for the purposes set forth. 50

JOHN SAMUEL DILLMAN.
